Primary Examiner — David G Muller*Assistant Examiner* — Nathan M Johnston(74) *Attorney, Agent, or Firm* — Dunlap Bennett & Ludwig PLLC; Brendan E. Squire(57) **CLAIM**

The ornamental design for a medical equipment stand, as shown and described.

DESCRIPTION

FIG. 1 is a front perspective of a medical equipment stand showing my new design;

FIG. 2 is a front elevation view thereof;

FIG. 3 is a rear elevation view thereof;

FIG. 4 is a left side elevation view thereof;

FIG. 5 is a right side elevation view thereof;

FIG. 6 is a top plan view thereof; and,

FIG. 7 is a bottom plan view thereof.

The broken lines shown in the drawings illustrate portions of the medical equipment stand that form no part of the claimed design.

The medical equipment stand is shown with a symbolic break in its length. The appearance of any portion of the article between the break lines forms no part of the claimed design.
